Primary Examiner—Ian Simmons*Assistant Examiner*—R. Johnson(74) *Attorney, Agent, or Firm*—Margaret Polson; Oppedahl Patent Law Firm LLC(57) **CLAIM**

The ornamental design for handicapped pants, as shown and described.

DESCRIPTION

FIG. 1 is a top plan view of handicapped pants showing my new design, the broken lines indicate stitching.

FIG. 2 is a front side elevation view of FIG. 1; and,

FIG. 3 is a top plan view of FIG. 1.

The broken lines, shown throughout the views, represent stitching.
